US0D1092142S

(12) **United States Design Patent** (10) Patent No.: **US D1,092,142 S**
(45) Date of Patent: ** Sep. 9, 2025

(54) **BEATER FOR A COOKING APPLIANCE**

(71) Applicant: **Tineco Intelligent Technology Co., Ltd.**, Suzhou (CN)

(72) Inventor: **Haoqiang Zhang**, Suzhou (CN)

(73) Assignee: **TINECO INTELLIGENT TECHNOLOGY CO., LTD**, Suzhou (CN)

(**) Term: **15 Years**

(21) Appl. No.: **29/832,460**

(22) Filed: **Mar. 28, 2022**

(30) **Foreign Application Priority Data**

Sep. 30, 2021 (CN) 202130653281.1

(51) **LOC (15) Cl.** **31-00**

(57) **CLAIM**

The ornamental design for a beater for a cooking appliance as shown and described.

DESCRIPTION

FIG. 1 is a perspective view of a beater for a cooking appliance;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings illustrate portions of the beater for a cooking appliance that form no part of the claimed design.

1 Claim, 7 Drawing Sheets
